J. A. LAMONT.

CAR BOLSTER.

APPLICATION FILED OCT. 2, 1905. RENEWED APR. 25, 1908.

926,752.

Patented July 6, 1909.

UNITED STATES PATENT OFFICE.

JOHN ALEXANDER LAMONT, OF MONTREAL, QUEBEC, CANADA, ASSIGNEE TO DOMINION CAR & FOUNDRY COMPANY, LTD., OF MONTREAL, CANADA, A CORPORATION.

CAR-BOLSTER.

No. 926,752.

Specification of Letters Patent.

Patented July 6, 1909.

Application filed October 9, 1905. Serial No. 221,091. Renewed April 25, 1909. Serial No. 429,349.

To all whom it may concern:

Be it known that I, JOHN ALEXANDER LAMONT, of the city of Montreal, Province of Quebec, Canada, have invented certain new and useful Improvements in Car-Bolsters; and I do hereby declare that the following is a full, clear, and exact description of the same.

The invention may be said briefly to consist of a car bolster comprising a T-iron (constituting the filler) having its long leg or web sheared off to the form of bolster required, a pair of angle irons bent to conform to the sheared off long leg or web and riveted thereto, while such long leg or web is slotted and with a pair of castings constitute a reinforced socket for completely inclosing the end of the king bolt, the said socket being formed with a key way.

For full comprehension, however, of my invention reference must be had to the accompanying drawings forming a part of this specification in which similar reference characters indicate the same parts and wherein

Figure 1 is a plan view of a body bolster constructed according to my invention; Fig. 2 is a side elevation thereof; Fig. 3 is a part side elevation and part longitudinal sectional view of the middle portion drawn to a larger scale than Figs. 1 and 2; Fig. 4 is a transverse vertical sectional view taken through the center of Fig. 3 and drawn to the same scale; Fig. 5 is an enlarged perspective view of the casting for reinforcing the king pin socket; Fig. 6 is a part plan and part horizontal sectional view of the portion of the bolster illustrated in Figs. 3 and 4 and drawn to the same scale; and Fig. 7 is a perspective view of the middle portion of my improved bolster partly broken away to illustrate the internal construction.

My improved bolster consists of a T-iron the web or long leg, *b*, whereof is sheared off to the form of bolster required, and a pair of angle-irons *a*, *c*, bent to conform to the sheared off edge of the T-iron are riveted to opposite sides thereof. The center of the T-iron is cut out as at *d* to receive the king bolt, and the portions of the angle irons contiguous thereto are bent outwardly, (as at *e*), to form with the opening *d*, a cylindrical socket with its inner side open for the king bolt. A pair of castings *f*, *f*, for reinforcing this socket and closing the upper end thereof are made to fit snugly upon the bent portions of

the angle irons and form an inclosing shield for the open inner end of the socket. To this end the outwardly curved portion of each casting is preferably of reduced diameter at its inner end *g*, the corresponding portions of the two castings constituting incidentally reinforcing the configuration portion of the T-iron.

The main reinforcing portion *h* of the casting and the bent out portions of the angle irons are coincidentally slotted as at *k* and *m*, respectively, to provide a key-way. The top and bottom plates *n* and *o*, respectively, are riveted to the flanges of the T-iron and the angle irons, and when a car body is constructed according to my invention the usual center plate *p* and side bearings *q* are riveted to the underside thereof. All that which is between the top and bottom plates of a bolster is known as the filler.

What I claim is as follows:

1. A bolster consisting of a T-iron and angle irons formed to conjointly present a socket for the king bolt.

2. A bolster consisting of a T-iron extending continuously from end to end of the bolster, a pair of angle irons secured to the opposite sides of the web or long leg of such T-iron, and means constituting with the T-iron a socket for a king bolt.

3. A bolster consisting of a T-iron extending continuously from end to end of the bolster and having the edge of its web or long leg sheared off to conform to the bolster of which it forms a part, a pair of angle-irons bent to conform to the sheared off edge and secured to the opposite sides thereof; top and bottom plates secured upon the flanges presented by the said T-iron and angle irons, and means forming a socket for the king bolt.

4. A bolster consisting of a T-iron having a transverse slot midway of its length, a pair of angle irons secured to the opposite sides of the web or long leg of such T-iron, such angle irons having outwardly curved portions constituting with the slot in the T-iron, a socket for the king bolt.

5. A bolster consisting of a T-iron having a transverse slot midway of its length, a pair of angle irons secured to the opposite sides of the web or long leg of such T-iron, such angle irons having outwardly curved portions constituting with the slot in the T-iron, a socket for the king bolt, and a pair of castings reinforcing such socket.

6. A bolster consisting of a T-iron, having the edge of its web or long leg sheared off to conform to the bolster of which it forms a part, such web or long leg having a transverse slot midway of its length; a pair of angle-irons bent to conform to the sheared off edge and secured to the opposite sides thereof, such angle-irons having outwardly curved portions forming with the slot in the T-iron a socket for the king bolt; a pair of castings riveted to opposite sides of the bolster and conforming to and reinforcing the socket; and top and bottom plates secured upon the flanges presented by the said T-iron and angle irons.
7. A bolster the filler of which has a transverse slot adapted to receive one end of the king bolt, and side members with portions contiguous to the slot curved outwardly and forming with such slot a socket for the king bolt.
8. A bolster comprising a filler having a transverse slot adapted to receive a king bolt, and a pair of castings forming with the slot a socket for the said king bolt.
9. A bolster the filler of which has a trans-
- verse slot adapted to receive one end of the king bolt, and side members with portions contiguous to the slot curved outwardly and forming with such slot a socket for the king bolt, and a pair of castings secured upon opposite sides of the filler and formed to conjointly inclose and reinforce such socket.
10. A bolster the filler of which has a transverse slot adapted to receive one end of the king bolt, and side members with portions contiguous to the slot curved outwardly and forming with such slot a king bolt socket with its inner end open, and a pair of castings secured upon opposite sides of the filler and formed to conjointly inclose and reinforce such socket, the said castings having portions adapted to conjointly close the open end of the socket.

In testimony whereof, I have signed my name to this specification, in the presence of two subscribing witnesses.

JOHN ALEXANDER LAMONT.
